Primary Examiner — Clare E Heflin(74) *Attorney, Agent, or Firm* — Yong Chen(57) **CLAIM**

The ornamental design for a solar dandelion light, as shown and described.

DESCRIPTION

FIG. 1 is a front view of a solar dandelion light of the present invention.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a first perspective view thereof; and,

FIG. 8 is a second perspective view thereof.

The broken line showing of certain portions of the solar dandelion light is included for the purpose of illustration only and forms no part of the claimed design.

1 Claim, 8 Drawing Sheets(56)
